UNITED STATES PATENT OFFICE.

LOUIS MANDEL, OF CHICAGO, ILLINOIS.

SINGLE-DIAL CONTROL FOR RADIO RECEIVING APPARATUS.

Application filed December 7, 1925. Serial No. 73,676.

This invention relates to improvements in mechanism for controlling the condensers of radio receiving apparatus, and one of the objects of the invention is to provide improved means whereby a plurality of condensers may be simultaneously adjusted or controlled.

In apparatus of this character and when controlling a plurality of condensers, generally three in number, although the condensers are of uniform inductance capacity, it has been found that there will always be a slight variation at various points of their inductance capacity.

Heretofore and in order to overcome this objection and difficulty, three separate controls have been provided, in a measure, for each of the variable condensers.

It is one of the objects of the present invention to provide improved means embodying a single operating device for actuating all of the rotors of the condensers until the desired capacity or wave length has been reached, and also means whereby certain of the stators may be given a free or independent movement or adjustment until all of the condensers are in perfect synchronism with each other.

A further object is to provide improved means of this character which will be of a simple and compact arrangement and which will be vernier in action.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a top plan view of an apparatus of this character constructed in accordance with the principles of this invention.

Figure 2 is a front elevation of Figure 1.

Figure 3 is a detail sectional view taken on line 3—3, Figure 2.

Figure 4 is a detail sectional view taken on line 4—4, Figure 1.

In the drawings three condensers A, B and C are shown, the condenser B being the central condenser and the condensers A and C the outermost condensers, all of which condensers are variable and are vernier in action.

These condensers are of the ordinary and

well known type embodying a stator and a rotor.

In the middle condenser B the stator, designated generally by the reference numeral 10 is stationary and is mounted in the usual manner, and co-operating with the stator 10 is a rotor 11 having the usual blades or plates which co-operate with the plates or blades of the stator.

The hub 12 of the rotor 11 has connected with it a stub shaft 13 projecting beyond one end thereof and a stub shaft 14 projecting beyond the other end thereof. The shaft 14 is journaled in a suitable bearing 15 and the shaft 13 is connected by means of a suitable coupling member 16 with the shaft 17 that is journaled in a suitable bearing 18. Connected with the coupling member 16 is a dial or indicator 19 which is provided with characters or designations 20 indicating different wave lengths or different stations.

The coupling member 16 is secured to the shafts 13 and 17 in any suitable manner such as by means of suitable fastening devices 21—22 so that the shafts and coupling member will rotate in unison.

A tension device of any suitable construction, preferably embodying a spring member 23 is provided, which is preferably of a slightly concave construction, the periphery or extremity of which contacts with the end member 24 of the stator 10. The shaft 13 passes through this member 23 and a nut or collar 25 is threaded upon the end of the shaft 13 and is adapted to be seated in a recessed portion 26 in the tension device 23 so that by adjusting the collar 25 suitable friction will be maintained against the end of the hub 12 of the rotor 11 and thereby provide the necessary friction for assisting in maintaining the parts in position.

The rotor 11 is adapted to be adjusted preferably by means of a worm gear 27 secured to the shaft 17, and a worm 28 meshes with the worm gear. This worm is connected with a shaft 29 having a handle or knob 30 thereon arranged in a convenient position for the operator, so that by rotating the knob 30 the shaft 29 will be rotated and through the medium of the worm 28 and worm gear 27 the dial 19 as well as the rotor 11 of the condenser B will be rotated or adjusted with respect to the stator 10.

The rotors of the outermost condensers A and C are also adapted for simultaneous rotation with the rotor 11, and this is accom-

plished by reason of the fact that the shaft 17 of the condenser C is connected with the coupling 16, and a similar shaft 31 of the condenser A is connected by means of a coupling 32 with the shaft 14 of the rotor 11 of the condenser B, the shaft 31 being journaled in a suitable bearing 31^a.

The construction of each of the condensers A and C is substantially the same and therefore the specific description of one will apply equally as well to them both.

The rotor of the condenser C embodies a hub 33 to which the blades 34 are connected, and the stator 35 is provided with end members 36-37. The shaft 17 which is connected with the hub 33 passes loosely through the end member 36 and a bearing 38 is formed about the opening in the end member 36, through which the shaft passes. A bearing member 39 is connected with the shaft 17 preferably by being threaded thereupon and this bearing member 39 co-operates with the bearing 38 in the end member 36 of the stator and is held in position against accidental displacement preferably by means of the fastening device 40, in the form of a screw or the like.

Passing loosely through the end member 37 of the stator is a screw or bolt member 41, the head of which rests against the outer face of the member 37, and the body element 41 is preferably threaded into the end of the hub 33. A tension member 42 provided with an open seat 43 encompasses the shank 35 of the element 41 and contacts with the end member 37, the body of the tension member 42 being shaped so that it will be spaced from the end member. A nut or collar 44 is threaded upon the shank of the element 41 and is seated within the recess 43 of the element 42, and also contacts with the end of the hub 33 of the rotor so that by adjusting the nut or collar 44 with respect to the element 41 the bearing member 39 will be held against the bearing 38 in the end member 36 and sufficient tension or friction will be created between these parts so as to hold the stator and also the rotor in their respective adjusted positions relative to each other.

With this construction it will be manifest that the rotor is adapted for a relative rotary adjustment with respect to the stator and the stator is also adapted for a relative rotary adjustment with respect to the rotor. Sufficient tension will be created between the parts of the condensers A and C so that when the knob or handle 30 is rotated to adjust the rotor of the condenser B the rotors of the condensers A and C will be correspondingly and simultaneously adjusted or rotated.

In these three condensers, although they are of uniform inductance capacity, there will always be a slight variation at various points in their inductance capacity and

therefore in order to control this variation in inductance means are provided whereby the stators of the outermost condensers A and C may also be adjusted with relation to the rotors of the respective condensers, and independently one with respect to the other and also with respect to the condenser B.

Inasmuch as the stators of the condensers A and C are mounted for pivotal or rotary adjustment, independently with relation to the respective rotors, any suitable means may be provided for securing such an adjustment and which adjusting means will be vernier in action.

To that end there is provided an adjusting device embodying a handle 45 which may be of any desired configuration but is preferably of a yoke like formation, the arms 46-47 of which are respectively pivoted to supports 48-49. The handle 45 is arranged in any convenient position for the operator.

Projecting from the arm 47 is a pin 50 which extends into a bifurcation 51 of a bracket 52, the latter being supported upon the stator in any suitable manner preferably by forming upon the end member 36 of the stator a bracket 53 which is shaped to form a bearing 54 for the end member and which bearing 54 co-operates with the bearing 18 to receive a sleeve or collar 55 in which the shaft 17 is directly journaled. This sleeve or collar 55 is preferably threaded in the bearings 18 and 54 and has a head 56 between which head and the adjacent face of the bearing 18 a spring device 57 is arranged so as to hold the sleeve or collar 55 in its adjusted position with respect to the bearings 18-54, and which spring 57 operates as a locking means for preventing accidental displacement or adjustment of the sleeve or collar 55 and at the same time holds the stator plate against being rotated by friction when the rotor plates are being rotated.

It will be noted that the stator 35 is pivotally mounted upon the shaft 17 and the pivots 58 and 59 of the arms 46-47 of the lever 45 are offset with respect to each other, thereby increasing the leverage and providing for a vernier adjustment of the stator.

The spring member 42 also serves as a means for holding the stator in its adjusted position with respect to the rotor.

The jaws of the bifurcation 51 are of a more or less spring construction so that the jaws will compensate or take up any lost motion between these parts.

The stator of the condenser A as well as the rotor are rotatable and independently adjustable in the same manner as the stator and rotor of the condenser C.

With this improved construction it will be manifest that when it is desired to "tune in" the handle or knob 30 is operated so as to simultaneously adjust the rotors of all three of the condensers and should there be

any slight variation of the condensers at various points of their inductance capacity all that is necessary is to adjust the handle 45 of either one or both of the outside condensers A and C in which the variation occurs until the three variable condensers are in perfect synchronism with each other, and as the lever action of the handles or adjusting devices 45 of the condensers A and C 10 are vernier in action it will be manifest that an accurate adjustment of the outside condensers one with respect to the other and also with respect to the condenser B may be readily obtained.

15 Obviously many changes may be made in the details of construction and in the combination and arrangement of the several parts, within the scope of the claims, without departing from the spirit of this invention.

20 What is claimed as new is:—

1. In combination, a plurality of condensers, each embodying a stator and a rotor, means operatively connecting the rotors for 25 simultaneous adjustment, the stator of one of said condensers being mounted for pivotal movement independently with respect to its rotor, a lever device for moving the stator about its pivot, the pivots of said lever and 30 stator being offset with respect to each other, and an operative connection between the lever and stator.

2. In combination, a plurality of condensers, each embodying a stator and a rotor, means operatively connecting the rotors for 35 simultaneous adjustment, the stator of one of said condensers being mounted for pivotal movement independently with respect to its rotor, a pivotally mounted actuating device, the pivot of said actuating device and 40 the said stator being offset one with respect to the other, and a pin and slot connection between the lever and the stator.

3. A condenser embodying a stator and a 45 rotor, said rotor embodying a hub like portion, means mounting the stator upon said hub like portion for pivotal movement with respect to the rotor, means for controlling the rotor, separate means for effecting a 50 vernier adjustment of the stator with respect to the rotor, the last recited means including a lever mounted upon a separate pivot, and an operative connection between the lever and the stator.

55 4. A condenser embodying a stator and a rotor, said rotor embodying a hub like portion, means mounting the stator upon said hub like portion for pivotal movement with respect to the rotor, means for controlling 60 the rotor, a lever mounted upon a pivot separate from and offset with respect to the pivot of the stator, and a pin and slot con-

nection between the lever and stator whereby 65 said lever will be vernier in action.

5. A condenser embodying a rotor, said rotor embodying a hub like portion, a stator pivotally mounted upon said hub, a bearing interposed between the stator and rotor, 70 means tending normally to hold the parts of the bearing in cooperative relation, means for controlling the rotor, and means for imparting a vernier adjustment to the stator with relation to the rotor.

6. A condenser embodying a rotor, said rotor embodying a hub like portion, a stator pivotally mounted upon said hub, means for controlling the rotor, means for effecting a vernier adjustment of the stator with respect 80 to the rotor, and friction creating means individual to the rotor and the stator and against the respective stresses of which last said means the stator and rotor are adjustable.

7. A device of the character described embodying a plurality of condensers, a single shaft for the condensers, means for rotating the shaft, actuating levers individual to certain rotatably mounted stator 90 frames, said levers mounted for free swinging movements, and means forming connections between the levers and the respective adjacent stator frames.

8. A device of the character described embodying a plurality of condensers, a single shaft for the condensers, means for rotating the shaft, pivotally mounted actuating levers individual to certain rotatably mounted stator frames, and means forming 100 connections between the levers and the respective adjacent stator frames, said levers being movable on pivots transverse to the axis of the stator to which it is connected.

9. A device of the character described embodying a plurality of condensers, a single shaft for the condensers, means for rotating the shaft, pivotally mounted actuating levers individual to certain rotatably mounted stator frames, and a pin and slot 105 connection between the levers and the respective adjacent stator frames.

10. A device of the character described embodying a plurality of condensers, a single shaft for the condensers, a turning 115 knob for rotating the shafts, stator frames rotatably mounted upon said shaft, members mounted for movement on pivots transverse to the axis of the shaft, and connections between the said members and the respective adjacent stator frames for rotating the latter.

In testimony whereof I have signed my name to this specification, on this 19th day of November, A. D. 1925.

LOUIS MANDEL.
